UNITED STATES PATENT OFFICE

ARTHUR BENJAMIN BROWNE, OF BRADFORD, CONNECTICUT.

BEST AVAILABLE COPY CARBURETER.

1,120,126.

Specification of Letters Patent.

Patented Dec. 8, 1914.

Application filed January 15, 1914. Serial No. 322,205.

To all whom it may concern:

Be it known that I, ARTHUR BENJAMIN BROWNE, a citizen of the United States, residing at Bradford, in the county of New Haven and State of Connecticut, have invented a new and useful Improvement in Carbureters; and I do hereby declare the following, when taken in connection with the accompanying drawings and the characters of reference marked thereon, to be a full, clear, and exact description of the same, and which said drawings constitute part of this application, and represent, in—

Figure 1 a side view of a carbureter constructed in accordance with my invention. Fig. 2 a top or plan view of the same. Fig. 3 a side view with the shells removed. Fig. 4 a view in vertical section. Fig. 5 a sectional view on the line *a—a* of Fig. 4. Fig. 6 a sectional view on the line *c—c* of Fig. 4.

This invention relates to an improvement in carbureters for supplying internal combustion motors with a combustible mixture of vapor-gas and air.

The object of this invention is to produce a carburetor particularly efficient in the use of low grade fuels at a low cost of manufacture without the sacrifice of efficiency, and to produce a carburetor by which easy starting may be secured when the engine is cold, and the invention consists in the construction hereinafter described and particularly recited in the claims.

When cold hydrocarbon fuels mix with air, if the rate of evaporation be relatively low, that is, if the fuel be comparatively non-volatile, it enters the air as a fine spray, but still liquid. Great difficulty is experienced in forcing evaporation of this spray which, if it reaches the cylinder as such, tends to poor combustion, as perfect gasification is necessary to the best results. The usual method of assisting evaporation consists of heating the air previous to the carburetion thereof and depending upon the transfer of this heat to the liquid spray received from the fuel nozzle. As the surface of the atomized particles is small, compared to the entire mass of air, this transfer of heat from the air to the fuel is relatively slow and evaporation of the liquid spray is correspondingly inefficient. Furthermore, heated air makes for poor volumetric efficiency because of the lesser density of the air when heated; that is to say, a cylinder full of heated air will not contain the same

weight of air as if the air were cold. When heated to or near its boiling point and subsequently atomized by a moving air column, the fuel changes to vapor instantly, and so speedily diffusing with the air even at low temperatures, makes a homogeneous fuel gas from which the great efficiency is obtained.

My invention consists primarily in heating the fuel immediately before it is atomized. This may be conveniently accomplished by preheated air, using the same air to form the gaseous mixture. In heating the fuel the air in itself is somewhat cooled before it enters the mixture, so that some of the volumetric losses are overcome. While for purposes of convenience and economy in manufacture, I prefer this method of heating the fuel, it is evident that other methods may be employed, as for instance heating the fuel by means of hot water from the engine jacket circulation, without departing from the essence of my invention, as, for instance, heating the fuel rather than heating the air, and I do not wish to be confined to the use of preheated air as a fuel heating medium, as controlling the flow of the fuel into the mixture I make use of the well known constant vacuum principle wherein a valve of constant weight opens under the suction of the engine an amount which admits the velocity of air necessary to maintain a vacuum equal substantially to the weight of the valve. This valve, operating by direct connection, controls the flow of fuel in direct proportion to the flow of air. The valve employed is of a type wherein the fuel issues through jets within the valve itself; and as will be shown, I have especially arranged the body of the valve and its seat and the location of these jets relative thereto so that they always open into the most constricted part of the venturi shaped air passage in whatever position the valve may assume thereby securing the highest atomization at all times, the reason that the air velocity at that point is greatest.

In one method of carrying out my invention, I employ an air inlet tube 2 externally threaded and screwed into a sleeve 3 of even the form at its upper end that its exterior surface forms a substantially straight line from the adjacent interior surface of the sleeve, the outlet from which is located the usual throttle valve 4. The sleeve 3 is formed at its lower end with a flange 5 to which is secured an inner cap 6 preferably formed from sheet

metal and having its lower edge 7 engaged with a shoulder 8 around the outside of the air tube 2. Around the inner cup 6 is an outer cup 9 larger in dimensions than the inner cup and having a lower flange 10 between which and the shoulder 8 is located a spacing ring 11, the vertical wall 12 of which is formed at intervals with openings 13 through which air may pass to the air tube 2. This outer shell is clamped to the lower edge of the ring by a lock nut 14 threaded onto the lower end of the air tube which also receives a metal cup 15. The outer shell is provided with an inlet opening 16 from which preheated air may be received from the engine.

At one side of the dome 3 is an opening 17 for connection with the supply of fuel. From this opening a passage 18 leads to the reservoir formed by the inner cup 6, the passage 18 being adapted to be closed by a valve stem 20 adapted to be moved by a float 21 hinged as at 22 to the dome, and so that as the float drops the valve will open, and as the float rises the valve will be closed. Within the air inlet tube 2 is a centrally arranged well 23 which communicates with the reservoir 19 by a channel 24 formed in one of the arms 25 formed as an integral part of the air tube 2 and supporting the well 23. Within the well is a piston 26 which fits the interior of the well 23 only close enough so that the device acts as a dash pot in retarding vibrations or pulsations of the hollow valve stem 27 which projects upward through the upper end of the well and which carries a valve 28. This valve is so shaped that the passage between it and the walls of the upper end of the air tube 2 and dome 3 is essentially venturi-shaped presenting the most efficient angle of approach and discharge to and from a constricted throat. Preferably the valve does not fully close the upper end of the air inlet tube but affords a slight area of admission even when in the extreme down position. The valve 28 is provided with a series of radial openings 29 connecting at their inner ends with the interior of the hollow valve stem 27 which stem has an opening 30 through the piston 26 into the well so that the fluid from the reservoir may pass from the well outward through the valve. The piston 26 carries a downwardly projecting needle valve 30 adapted to enter a valve seat 31 mounted in the lower end of the well and provided with ports 32 communicating with the passage 24 to the reservoir. This valve seat projects downward through the cup 15 and at its lower end may be closed by a screw plug 33, and through the lower end of the valve seat a pin or rod 34 may extend by which the valve seat may be turned so as to raise or lower the seat 35 with relation to the needle valve. Within

the cup 15 and around the lower end of the valve seat is a stuffing box 35. By arranging the needle valve and its seat so as to regulate the supply of fuel to the well rather than the former method of directly 70 regulating the discharge from the well, I derive the advantage that any fuel leaking into the mixture, as around the valve stem 27 in its passage through the upper end of the well 23, has first been accurately controlled by its passage through the valve seat 31 so that such leakage is without effect on the mixture. The valve stem 27 and the needle valve 30 are preferably made of material having a relatively high coefficient of 80 expansion, so that as the fuel becomes heated, the area of fuel admission through the valve seat 31 is decreased by the expansion and consequent lengthening of the valve stem 27 and the needle valve 30. By this 85 means I effect an automatic compensation for the decreasing viscosity of the fuel as the temperature rises.

Preferably and as herein shown, within the lower end of the well 23 and above the valve seat 31, I locate an electrical resistance coil 36 one end of which is grounded with the wall of the well, and the other end passing downward through the walls of the valve seat 31 to a binding post 37 insulated 95 from the carburetor body which is also provided with a binding post 38 by which connections may be made with a source of electric energy and so that when connections are made a current may be passed through 100 the coil.

The carburetor being connected to the engine and hot air connection being made as indicated, fuel is admitted through the opening 17 into the reservoir 19 from which it 105 flows through the passage 24, port 32, and valve seat 31 to the well 23, it being understood that when a predetermined quantity of fuel has entered the reservoir the float 21 will rise and lift the valve 20 so as to cut off 110 further supply. When the throttle 4 is open and the engine started, the suction of the engine creates a vacuum in the dome 3 and the velocity of the in-rushing air through the restricted area between the 115 valve 28 and the walls of the air tube 2 inspires the fuel from the well through the hollow valve stem 27 and holes 29, the fuel becoming highly atomized. As the suction increases the valve lifts further, admitting a greater quantity of air, and at the same time withdrawing the needle 30 from the valve seat 31 increasing the area of the latter and affording a proportional increased flow of fuel. Preheated air entering 120 through the opening 16 into the chamber formed between the two cups passes through the ring 11 and is drawn into the air tube 2 by the suction of the engine, and this heated air coming in contact with the 125

inner cup 6 heats the fuel to such a degree that it rapidly changes to vapor when drawn into the air, and at the same time this air in giving off its heat to the fuel within the cup or reservoir is cooled to a certain extent before it enters the air tube, so that a greater weight of air may be received than if it were admitted at higher temperature. It will be noted further that in starting, when the valve is nearly in its closed position, the air area is restricted so that owing to the inertia of the valve, the suction will first draw the liquid fuel so that a richer mixture is obtained.

In starting, when the engine is cold, in order to volatilize the fuel, electrical current is turned on through the coil 36 which will heat the small quantity of fuel within the well in a short time so that this portion of fuel within the well, forms what might be called a priming charge sufficient to start the engine, without the necessity of heating the entire amount of fuel in the reservoir which would take an impractical length of time with such current as is usually available. The engine, once started, soon preheats the air so as to heat the larger quantity of fuel contained in the reservoir.

With my improved device, and particularly by my method of employing pre-heated air to heat the fuel, I am enabled to use with great efficiency a low grade fuel, and at all times regulate the flow of fuel in direct proportion to the flow of air.

I claim:

1. A carbureter having its air inlet passage obturated by a valve the operative walls of which are of a different angle from those of its seat, said walls forming with said seat a constricted opening of the said air inlet passage, essentially venturi shaped in section, said valve being provided with means for discharging fuel at the point of greatest constriction of the air inlet passage.

2. A carbureter having an air inlet passage obturated by an air valve, the operative walls of which form with its seat a constricted opening of said air inlet passage essentially venturi shaped in section, said valve provided with a stem having a passage, a tapered needle operatively connected to said air valve, a stationary compartment into which said valve stem extends and into which the flow of fuel is controlled by said tapered needle and from which the fuel is withdrawn through the passage in the air valve.

3. A carbureter having an air inlet passage operated by an air valve, the operative

walls of which form with its seat a constricted opening of said air inlet passage essentially venturi shaped in section, said valve provided with a stem having a passage, a tapered needle operatively connected to said air valve, a stationary compartment into which said valve stem extends and into which the flow of fuel is controlled by said tapered needle and from which the fuel is drawn through the passage in the air valve the walls of said compartment co-acting with the stem of the said air valve and exerting a dampening effect on vibrations imparted to said air valve.

4. A carbureter having an air inlet passage obturated by an air valve combined with a jacketed fuel reservoir, a well, a fuel passage between said reservoir and said well, a tapered needle connected to and actuated by said air valve, said needle governing the effective area of said fuel passage, said air valve provided with a stem which enters said well and co-acts with the walls thereof to dampen vibrations imparted to said air valve, said stem and said air valve formed with connecting passages through which fuel is withdrawn from said well and discharged into said air inlet passage at the point of greatest constriction of said air inlet passage.

5. A carbureter having an air inlet passage opening into a chamber, combined with inner and outer shells fixed with relation to the walls of said air inlet passage in such a manner as to afford means of communication between the space formed between said shells and said air inlet passage, a fuel reservoir formed by said inner shell, a well, a passage for fuel between said reservoir and said well, a valve seat through which fuel is admitted to said well, a valve stem extending into said well and co-acting with the walls of said well to dampen vibrations imparted to said stem, a needle valve carried by said valve stem and co-acting with said valve seat to regulate the supply of fuel entering said well, a valve secured to said valve stem, said valve co-acting with the walls of said air inlet passage to regulate the quantity of air entering the said chamber, and a passage through said valve and stem whereby fuel is drawn from said well and caused to mix with said air.

In testimony whereof, I have signed this specification in the presence of two subscribing witnesses.

ARTHUR BENJAMIN BROWNE.
